(57) **CLAIM**

We claim the ornamental design of a perforating gun assembly, as shown and described.

DESCRIPTION

FIG. 1 is a front, top perspective view of a perforating gun assembly showing an embodiment of our new design; FIG. 2 is a left-side elevated view of the perforating gun assembly of FIG. 1;

FIG. 3 is a right-side elevated view of the perforating gun assembly of FIG. 1;

FIG. 4 is a top plan view of the perforating gun assembly of FIG. 1;

FIG. 5 is a bottom plan view of the perforating gun assembly of FIG. 1;

FIG. 6 is a front elevated view of the perforating gun assembly of FIG. 1;

FIG. 7 is a rear elevated view of the perforating gun assembly of FIG. 1; and,

FIG. 8 is a cross-section view of the perforating gun assembly taken along line 8-8 of FIG. 6 while in a usage state.

The broken lines consisting of dashes show an environment that forms no part of the claimed design. The broken lines consisting of a double-dot/dash pattern show a boundary of the claimed design.
